UNITED STATES PATENT OFFICE.

LUDWIG OBERHAMMER, OF MUNICH, GERMANY.

GEAR-CHANGING DEVICE FOR BICYCLES.

SPECIFICATION forming part of Letters Patent No. 624,964, dated May 16, 1899.

Application filed July 9, 1898. Serial No. 685,509. (No model.)

To all whom it may concern:

Be it known that I, LUDWIG OBERHAMMER, a subject of the King of Bavaria, residing at Munich, Kingdom of Bavaria, Germany, have 5 invented certain new and useful Improvements in Gear-Changing Devices for Chainless Bicycles, of which the following is a full, clear, and exact description.

This invention relates to gear-changing devices for chainless bicycles; and it consists, substantially, in such features of improvement as will hereinafter be more particularly described.

In order to render the present specification 15 more easily understood, reference is had to the accompanying drawings, in which similar letters of reference denote similar parts throughout the several views.

Figure 1 is a longitudinal section through 20 the rear-wheel axle and the rear part of one of the arms of the rear-wheel fork. Fig. 2 is a side elevation of Fig. 1; Fig. 3, a section on line 33 of Fig. 1. Figs. 4, 5, and 6 are details of certain grooves hereinafter set forth. 25 Fig. 7 is a detail of the end of the support for the rear-wheel axle. Fig. 8 is a sectional elevation of the front-wheel-fork guiding-sleeve; Fig. 9, a cross-section on the line 99 of Fig. 8; Fig. 10, a part elevation of the front-fork guide-sleeve seen from the rear, and Fig. 30 11 a detail sectional elevation of a device for effecting the change of gear.

As is well known, in the construction of chainless bicycles, on one arm *a* of the rear fork of the machine a hollow sleeve *b* rotates, 35 and on and in this sleeve is mounted the gear-changing device forming one of the principal features of the present invention. The bevel-gears *c* and *d* are mounted to rotate freely on ball-bearings on the said sleeve *b*, and fast to the latter is a collar *f*, which supports and forms one of the ball-bearings for each gear *c* and *d*, while the cup *e* is screwed upon the end of the sleeve *b* and 40 forms, together with the collar *u*, the end ball-bearing for the said sleeve *b*. Within the end of the sleeve *b* is mounted loosely a short sleeve *g*, encircling the arm *a* and connected to a rod *i*, extending out at the end of 45 the hollow arm *a* by means of a pin (not shown) which passes through the slot *h* in said arm *a*, and thus the rod *i* and also the sleeve *g* are

55 prevented from rotating with the sleeve *b*. Revolubly mounted on the sleeve *g*, but longitudinally confined on the same by means of end flanges *g*² *g*² on the sleeve is a second sleeve *h*, having lugs *m*, advantageously two in number, and this sleeve effects the coupling of one or other of the beveled gears *c* or *d* to the sleeve *b*. The lugs *m* of the said coupling-sleeve *h* extend through slots *n* of the sleeve *b* and are capable of engagement with corresponding grooves *o* and *p*, longitudinally cut in the interior of the bosses of the 60 said bevel-gears *c* and *d*. The collar *f* is also 65 recessed at the corresponding points of the interior of its boss to allow the said lugs of the coupling-piece *h* to pass from one side of the collar to the other. The longitudinal movement of the coupling-piece *h* is effected 70 by means of the sleeve *g* and the rod *i*. The two gears *c* and *d* are in engagement with the double bevel-gear *q*, mounted in the well-known manner on the rear-wheel axle *r*. Thus if the rod *i* is pushed inwardly—*i. e.*, 75 from right to left of Fig. 1—its lugs *m* will pass out of engagement with the grooves *p* of the gear *d* and into engagement with those, *o*, of the bevel-gear *c*, thus changing the gearing to the higher-speed gearing. 80

In order to enable the lugs *m* to easily find their way into the grooves of either wheel, the adjacent faces of the bosses of said wheels are provided with inclined thread-like depressions *o*⁶, as will be clearly seen from Figs. 4, 85 5, and 6, which inclines lead into the said grooves from the side. Thus as the sleeve *b* rotates and the part *h* is shifted so as to contact with the corresponding face of the other gear in coming around the lugs *m* will be 90 forced against the inclines by the push of the rod *i* and will abut against the side of the grooves, so that they may be then easily pushed into said grooves. Fig. 6 shows the projection or rolled-out interior surface of the 95 boss-boring, showing the form and location of the said grooves or inclines.

In order to enable the adjustment of the rear-wheel axis to and from the crank-axle, the said axis is formed with a fork *v* at the 100 end, which engages over the end of a sleeve *t* on arm *a* and against the flange *t*' of the same. The said fork is provided with an upwardly-extending eye *s*, to which the lower

end of one of the arms of the fork extending down from the saddle is attached, and the rear face of the said fork is covered with a plate w , advantageously screwed thereto at 5 10 and having an orifice therein just large enough to allow the end of the arm a to pass through it. The collar u is also mounted on the said sleeve t and is adjustable thereon, being held in position by means of the lock-nut u' . From the foregoing it will be evident that by adjusting the position of the flange t' and the lock-nut x outside of the fork the position of the rear-wheel axle r may be varied at will, according to requirement.

15 The preferred means for operating the rod i will now be described. In a bearing y' , mounted in proximity to the sleeve z for the stem of the steering-bar, is supported a shaft z' , to which is keyed a disk s' , having in its 20 face two diametrically opposite orifices o' , and loosely mounted on shaft z' is a toothed segment q' , which is in engagement with the teeth of a rack-sleeve y , loosely encircling the stem l of the steering-bar. The segment q' is provided in its face, adjacent to the disk s' , with a spring-pressed pin n' , adapted to engage the orifices of the said disk s' , said pin having its 25 end beveled off, (not shown,) and when the segment is moved on its pivot in one direction it will be coupled to the said disk; but on the backward stroke it will disengage from the same by means of the said beveled-off end. The sleeve y is spring-pressed upwardly by any suitable well-known means (not shown) 30 and is capable of depression by the rod v' , having button l' and extending out at the top of the stem of the steering-bar. The lower end of the rod v' is provided with a laterally-extending lug w' , which engages loosely in a 35 corresponding slot w^2 in the stem l , and it will be seen that on turning the said stem l from the steering-bar (not shown) the relation of the teeth on the rack-sleeve with those on the segment q' will not be disturbed, since the 40 teeth of said sleeve extend all the way around the same. The shaft z' is provided with a crank-arm r' , which is connected by a rod m' to any suitable lever in connection with the 45 end of the rod i , so as to push the said rod inwardly or pull the same outwardly when the 50 said crank-arm is turned half a revolution.

The operation of this device will be evident from the foregoing description. As soon as the button is depressed the disk s' , which is 55 engaged by the pin of the segment q' , turns with the latter half a turn, and with it the disk, the crank r' , which is also keyed to the shaft z' . On this taking place the gearing is changed, and as soon as the lugs m on sleeve 60 h have properly engaged the other bevel-wheel and after the rod v' has been released the sleeve y , and with it the rod v' , will be actuated upwardly, and on the upward movement of said sleeve and rod the sleeve will 65 return the segment q' to its initial position, since the pin n' will become disengaged from one of the orifices o' , and on reaching its ini-

tial position it will again engage the other orifice, so that the parts are again in readiness to again change the gearing. The bearing y' is advantageously fixed to the upper end of the frame-bar x' , as shown at Figs. 8 and 10.

Although the device has been described with reference to a change of two gearings, it 70 is obvious that three gearings might be employed by the same device, in which case three bevel-gears would be arranged and the center one would have to be provided with the leading-in inclines at both its faces, as 75 will be readily understood. The disk s' also would have to be provided with three orifices for properly adjusting the rod i ; but as a rule not more than two gearings are employed.

I claim as my invention—

85 1. In a multiple-gear cycle, the combination of a series of beveled gears engaging a multiple gear on the drive-shaft, and provided with bosses having parallel grooves, and also provided on their adjacent faces with 90 semicircular inclined planes leading to the grooves, and a clutch device comprising in part a rotatable sleeve provided with lugs adapted to enter the grooves in the bosses, substantially as described.

95 2. In a multiple-gear cycle, the combination of a series of beveled gears engaging a multiple gear on the drive-shaft, and having bosses provided with parallel grooves, and also provided at their ends with semicircular 100 inclined planes leading to the grooves, and a clutch device comprising a rotatable sleeve having lugs adapted to enter the said grooves from the ends, a non-rotatable longitudinally-movable sleeve passing through said rotatable sleeve and engaging the ends of the same, and means for operating said second-named sleeve, substantially as described.

110 3. In a multiple-gear cycle, the combination of a series of beveled gears engaging a multiple gear on the drive-shaft, and having bosses provided with parallel grooves, and also provided at their ends with semicircular 115 inclined planes leading to the grooves, and a clutch device comprising a rotatable sleeve having lugs for entering the grooves, a non-rotatable longitudinally-movable sleeve within said rotatable sleeve, the same being provided with end flanges engaging the latter, and a movable rod for operating said non-rotatable sleeve, substantially as described.

120 4. In a multiple-gear cycle comprising a series of bevels to engage a multiple bevel on the driving-wheel shaft, and means for coupling either one of said bevels to the rotating member of the machine, consisting of an interior sliding coupling-piece as specified, the means for operating said sliding coupling, consisting of the combination of an upwardly-spring-pressed threaded sleeve y loosely 125 mounted on the steering-bar stem within the guide-sleeve of the same, a toothed segment and a shaft z' mounted in proximity to the said threaded sleeve, on which said segment

is loosely mounted to engage the said threaded sleeve, a disk fast on said shaft, and a crank also fast thereon, and a connecting-rod with means for transferring the motion of said 5 crank to the coupling-shifting bar, and means in connection with said toothed segment to couple the same to said disk when the threaded sleeve is depressed, and to uncouple the same when the said sleeve rises, and means for 10 again coupling said segment and disk when the segment has regained its initial position substantially as described.

5. In a multiple-gear cycle of the kind specified the means for shifting the coupling-piece 15 consisting of the combination of a shaft z' mounted in proximity to the steering-bar stem, a toothed segment q' loosely mounted thereon, a disk and a crank-arm keyed to said shaft, said disk having orifices $o' o'$, a spring-pressed 20 pin n' mounted in the face of the segment adjacent to and in the circular path of the said orifices, said pin having beveled end as specified, a rack-sleeve loosely inclosing the steering-bar stem and in engagement with

the said segment, said sleeve being spring- 25 pressed upwardly, a rod v' having lateral lug w' to engage said threaded sleeve and allow longitudinal play of the same, and means for transmitting the motion of the said crank-arm, when the said rod and sleeve are depressed, to the said sliding coupling in the 30 manner and for the purpose substantially as described.

6. The combination with the fork-arm for the driving-wheel, of a threaded sleeve thereon, a fork embracing said arm at the outer end of the sleeve, and having a flange against which said fork-arm abuts, a plate secured to the outer face of the fork, and provided with an opening through which said fork-arm for 40 the wheel passes, and a lock-nut bearing against said plate, substantially as described.

In witness whereof I have hereunto set my hand in presence of two witnesses.

LUDWIG OBERHAMMER.
